CLAIM

The ornamental design for a mobile communication device, as shown and described.

DESCRIPTION

FIG. 1 is a front perspective view of the mobile communication device.

FIG. 2 is a rear perspective view of the mobile communication device.

FIG. 3 is a top view of the mobile communication device.

FIG. 4 is a bottom view of the mobile communication device.

FIG. 5 is a right side view of the mobile communication device.

FIG. 6 is a left side view of the mobile communication device.

FIG. 7 is a front view of the mobile communication device; and,

FIG. 8 is a rear view of the mobile communication device.

1 Claim, 6 Drawing Sheets
